UNITED STATES PATENT OFFICE

155,894

DESIGN FOR A COMBINED CHILD'S WAGON AND PROTECTING COVER

Le Roy A. Hedlund, Marshalltown, Iowa

Application March 19, 1948, Serial No. 145,207

Term of patent 14 years

(Cl. D34—15)

To all whom it may concern:

Be it known that I, Le Roy A. Hedlund, a citizen of the United States, residing at Marshalltown, Iowa, in the county of Marshall and State of Iowa, have invented a new, original, and ornamental Design for a Combined Child's Wagon and Protecting Cover, of which the following is a specification, reference being had to the accompanying drawing, forming part thereof.

I claim:

The ornamental design for a combined child's wagon and protecting cover, as shown.

LE ROY A. HEDLUND.
